US00D612611S

(12) **United States Design Patent**
Brown, Jr. et al.

(10) **Patent No.:** US D612,611 S
(45) **Date of Patent:** ** Mar. 30, 2010

(54) **HEAD OF A TOOTHBRUSH**

1,327,757 A 1/1920 Eggers

(75) Inventors: **William Ralph Brown, Jr.**, Peabody, MA (US); **Alexander Timothy Chenvainu**, Sudbury, MA (US); **Thomas Aurele Christman**, Lexington, MA (US)

(Continued)

(73) Assignee: **The Gillette Company**, Boston, MA (US)

FOREIGN PATENT DOCUMENTS

DE 10208529 C1 10/2003

(**) Term: **14 Years**

(Continued)

(21) Appl. No.: **29/313,888**

CLAIM

(22) Filed: **Feb. 17, 2009**

The ornamental design for a head of a toothbrush, as shown and described.

DESCRIPTION

(63) Continuation of application No. 29/265,465, filed on Aug. 31, 2006, now abandoned, which is a continuation-in-part of application No. 29/204,170, filed on Apr. 26, 2004, now abandoned, which is a continuation-in-part of application No. 29/194,039, filed on Nov. 18, 2003, now Pat. No. Des. 501,605, which is a continuation-in-part of application No. 10/364,148, filed on Feb. 11, 2003.

FIG. 1 is a perspective view of a head of a toothbrush, embodying the new design;

(51) **LOC (9) Cl.** **04-02**

FIG. 2 is a top planar view of the head of a toothbrush of FIG. 1;

(52) **U.S. Cl.** **D4/101; D4/111**

FIG. 3 is a left side elevational view of the head of a toothbrush of FIG. 1, the right side elevational view being a mirror image;

(58) **Field of Classification Search** D4/101,

FIG. 4 is a bottom planar view of head of a toothbrush of FIG. 1;

D4/104–112, 127, 130, 136; 15/22.1, 28,
15/29, 110, 167.1, 167.2; 433/116, 125,
433/166; 132/308–311; 601/139, 141, 142

FIG. 5 is a front elevational view of the head of a toothbrush of FIG. 1; and,

See application file for complete search history.

FIG. 6 is a rear elevational view of the head of a toothbrush of FIG. 1.

(56) **References Cited**

The claim ends with the surface shading immediately below the rounded edge of the face of the head. The broken lines illustrate portions of the head that form no part of the claimed design.
